STABILIZING BRACE OR SIMILAR ARTICLE

Albert L. Conwill, Vincent, Ala., assignor to Beaunit Corporation, New York, N.Y., a corporation of New York

Filed July 30, 1969, Ser. No. 18,465

Term of patent 14 years

Int. Cl. D8—99

U.S. Cl. D8—233

FIG. 1.

FIG. 2.

FIG. 1 is a front view of a stabilizing brace or similar article, showing my new design.

FIG. 2 is a side view thereof.

The side opposite that shown in FIG. 1 is substantially a mirror image thereof, and the remaining sides are substantially identical to the side shown in FIG. 2.

I claim:

The ornamental design for a stabilizing brace or similar article, as shown and described.
